(57) **CLAIM**

The ornamental design for a dental instrument, as shown and
described.

DESCRIPTION

FIG. 1 is a perspective view of the dental instrument showing
our new design;

FIG. 2 is a top plan view thereof;

FIG. 3 is a bottom plan view thereof;

FIG. 4 is a first side elevational view thereof;

FIG. 5 is a second side elevational view thereof;

FIG. 6 is a front elevational view thereof; and,

FIG. 7 is a back elevational view thereof.

The broken lines in the figures represent portions of the dental
instrument that form no part of the claimed design.
